CHECK-PAD HOLDER

Evangel A. Haveles, Los Angeles, Calif.

Application March 16, 1938, Serial No. 196,220

10 Claims. (Cl. 281—1)

My invention relates to check-pad holders, particularly adapted for holding pads used for counter service, such as restaurant check pads or the like, and is particularly adapted for use in connection with the diagonal shield positioned near the back of the counter between the customer and the waiter, and the objects of my invention are:

First, to provide a check-pad holder of this class which may be readily and quickly clamped upon the upper edge of the diagonal shield and is easily and readily removed therefrom when desired;

Second, to provide a holder of this class which is applicable for varying thickness diagonal shields and varying angles for the diagonal shield;

Third, to provide a simple check-pad holder of this class which supports the pad substantially rigid in its position and so that it is readily accessible to the user of the check pad and permits the removal of one check at a time easily therefrom;

Fourth, to provide a check-pad holder of this class that may be readily secured to the diagonal shield without in any way marring the shield at the place where it is secured;

Fifth, to provide a check-pad holder of this class which supports the check pad in a substantially horizontal position without regard to the angle of the diagonal shield on which it is supported; and

Sixth, to provide a check-pad holder of this class which is very simple and economical of construction, easy to shift from place to place on the shield, easy to replace pads therein and which will not readily deteriorate or get out of order.

With these and other objects in view as will appear hereinafter, my invention consists of certain novel features of construction, combination, and arrangement of parts and portions as will be hereinafter described in detail and particularly set forth in the appended claims, reference being had to the accompanying drawing and to the characters of reference thereon which form a part of this application, in which:

Figure 1 is a top or plan view of my check-pad holder shown in substantially horizontal position; Fig. 2 is a side elevational view thereof and showing a fragmentary portion of the upper edge of the shield on which said check-pad holder is mounted ready for use; Fig. 3 is a front elevational view thereof facing toward the waiter, and Fig. 4 is a side elevational view of my check-pad holder in a slightly modified form from the

other views of the drawing and showing it in position on a fragmentary portion of the upper edge of a shield.

Similar characters of reference refer to similar parts and portions throughout the several views of the drawing.

The clamp member 1, clamp screw 2, pad holder 3, pad holder clamp 4, and pad holder support 5 constitute the principal parts and portions of my check-pad holder.

The clamp member 1 is provided with a substantially vertical portion 1a. The lower sides of this vertical portion 1a is turned backwardly at 1b shown best in Fig. 2 of the drawing. This portion 1b is reinforced in its relation with the portion 1a by means of two integral offset reinforcing portions 1c and 1d. Mounted in this portion 1b, which is provided with a screw thread hole 1e is the clamping screw 2, the one end of which is adapted to fit up against the lower side 20 of the upper edge of the diagonal shield for clamping the holder in position on the shield, as shown best in Fig. 2 of the drawing. This clamp screw 2 is provided with a head 2a to facilitate the turning of said screw for clamping the holder in position on the shield. The pad holder member 3 is a substantially flat member integrally connected to the member 1 at its upper edge as shown best in Fig. 2 of the drawing, and it is substantially the size of the pad which is to be mounted thereon. This member 3 is provided with upwardly extending flanges 3a and 3b which are adapted to cover a portion of the sides of the pad when it is in position and prevent its slipping sidewise. The back end of the member 3 is provided with a depressed portion 3c which permits the support of the clamp member 4 so that the upper edge of the lower side of the clamp member is flush with the upper face of the holder.

3. In this depressed portion is provided a U-shaped in cross section spring clamp member 4 which fits in this depressed portion at one side at 4a and extends upwardly the height of the pad at 4b and forms the end for the pad and is also provided with a backwardly extending spring portion 4c which fits tightly against the upper side of the pad at its clamped end shown best in Fig. 2 of the drawing. This clamp member 4 is provided with a slot 4d in its upper side into

which a portion of the upper section of the pad 50 protrudes when the pad is forced into the spring clamp member 4, thus securing the pad rigidly in position. Secured substantially centrally on the lower side of the member 3 is the pad holder supporting member 5, which is an L-shaped metal 55

plate provided with a substantially horizontal portion 5a which is secured to the lower side of the member 3 by spot welding, or otherwise, and with a downwardly extending portion 5b which is provided with a tapered lower edge 5d adapted to substantially fit the angle of the upper side or surface of the shield as shown best in Fig. 2 of the drawing.

In the modified form of construction shown in Fig. 4 of the drawing the construction is the same as that in Figs. 1, 2, and 3 of the drawing except as follows:

The clamp member 1 and bolt 2 are omitted and there is provided a downwardly extending apron member 6 which extends downwardly only a short distance and is provided with indented portions 6a, the upper sides of which are adapted to rest against the lower upper edge of the shield. The member 5 is secured to the lower side in the same manner, but it is provided with a slot positioned vertically therein, 5c, which is adapted to receive a screw bolt 7a which supports an adjustable supporting member 7 which has a hole therein for receiving said screw bolt 7a which extends through said hole and through the slot 5c and is adapted to clamp the member 7 relatively to the member 5 in various angular and adjusted positions dependent upon the thickness and angle of the shield. This member 7 is provided with rounded ends 7b and 7c, as shown.

The operation of my check-pad holder is as follows:

The clamp member 1 is clamped in position on the upper edge of the diagonal shield with the clamp side toward the waiter or operator and the screw member 2 is tightened against the lower side of the upper edge of said shield. The pad with the secured end is forced into the clamp member 4 between the portions 4a and 4c against the portion 4b, then the operator may write on the check or punch the same and tear it off at the edge of the portion 4c and it is ready for another customer. The clamp member 1 may be shifted to various positions as desired along the edge of the shield. The support 5 provides a means for supporting the main portion of the holder on the upper surface of the shield.

In the modified form of construction, the shield is positioned in the turned portion, the lower side resting against the indented portion 6a and the one side of the member 7 resting against the upper surface of the shield in varying adjusted positions so that the body is substantially horizontal.

Though I have shown and described a particular construction, combination, and arrangement of parts and portions and a certain modification, I do not wish to be limited to this particular construction, combination, and arrangement, nor to the modification, but desire to include in the scope of my invention the construction, combination, and arrangement substantially as set forth in the appended claims.

Having thus described my invention, what I claim as new and desire to secure by Letters Patent is:

1. In a check-pad holder, the combination with a diagonal shield, of a check-pad holder provided with a screw clamp member at one end adapted to engage and clamp against the upper edge of said diagonal shield and provided with a downwardly extending support intermediate its ends of sufficient length to engage the upper side 75 of said diagonal shield and hold said check-pad

holder in a substantially horizontal position on said diagonal shield.

2. In a check-pad holder, the combination with a diagonal shield on a counter, of a check-pad holder provided with a screw clamp member at one end adapted to engage and clamp against the upper edge of said diagonal shield and provided with a downwardly extending support intermediate its ends of sufficient length to engage the upper side of said diagonal shield and hold said check-pad holder in a substantially horizontal position on said diagonal shield, said check-pad holder provided with a U-shaped spring clip adapted to receive one end of a check pad.

3. In a check-pad holder, the combination with a diagonal shield on a counter, of a check-pad holder provided with a screw clamp member at one end adapted to engage and clamp against the upper edge of said diagonal shield and provided with a downwardly extending support intermediate its ends of sufficient length to engage the upper side of said diagonal shield and hold said check-pad holder in a substantially horizontal position on said diagonal shield, said check-pad holder provided with a U-shaped spring clip 25 adapted to receive one end of a check pad, said check-pad holder also provided with upwardly extending side flanges.

4. In a check-pad holder, the combination with a diagonal shield, of a check-pad holder including a downwardly extended portion at one end adapted to fit over the upper edge of said diagonal shield, a downwardly extending support secured to said check-pad holder and extending downwardly adapted to engage the upper surface of said diagonal shield for supporting said check-pad holder in a substantially horizontal position on said diagonal shield, said downwardly extending support composed of two relatively shiftable members for adjustment.

5. In a check-pad holder, the combination with a diagonal shield, of a check-pad holder including a downwardly extended portion at one end adapted to fit over the upper edge of said diagonal shield, a downwardly extending support secured to said check-pad holder and extending downwardly adapted to engage the upper surface of said diagonal shield for supporting said check-pad holder in a substantially horizontal position on said diagonal shield, said downwardly extending support composed of two relatively shiftable members for adjustment, said check-pad holder also provided with a U-shaped spring clip adapted to receive one end of a check pad.

6. In a check-pad holder, the combination with a diagonal shield, of a check-pad holder including a downwardly extended portion at one end adapted to fit over the upper edge of said diagonal shield, a downwardly extending support secured to said check-pad holder and extending downwardly adapted to engage the upper surface of said diagonal shield for supporting said check-pad holder in a substantially horizontal position on said diagonal shield, said downwardly extending support composed of two relatively shiftable members for adjustment, said check-pad holder also provided with a U-shaped spring clip adapted to receive one end of a check pad, said check-pad holder also provided with upwardly extending side flanges.

7. In a check-pad holder, the combination with a diagonal shield, of a check-pad holder provided with a U-shaped spring clip adapted to receive one end of a check pad and clamp the same, and also provided with upwardly extending side 75

flanges for preventing the pad from turning therein, a support secured to the lower side of said check-pad holder intermediate its ends and extending downwardly for engagement with the upper side of said diagonal shield, said check-pad holder provided with a downwardly and backwardly extending portion adapted to engage the lower side of the upper edge of said diagonal shield.

5 8. In a check-pad holder, the combination with a diagonal shield, of a check-pad holder provided with a U-shaped spring clip adapted to receive one end of a check pad and clamp the same, and also provided with upwardly extending side flanges for preventing the pad from turning therein, a support secured to the lower side of said check-pad holder intermediate its ends and extending downwardly for engagement with the upper side of said diagonal shield, said 15 check-pad holder provided with a downwardly and backwardly extending portion adapted to engage the lower side of the upper edge of said diagonal shield, and clamp means mounted in said backwardly extended portion for clamping

the lower side of the upper edge of said diagonal shield.

9. In a check-pad holder, the combination with a diagonal shield, of a check-pad holder provided with a downwardly extending support intermediate its ends arranged to engage the upper side of said diagonal shield, said check-pad holder also provided with a downwardly and backwardly extending portion adapted to engage the lower side of the upper edge of said diagonal shield. 5

10. In a check-pad holder, the combination with a diagonal shield, of a check-pad holder provided with a downwardly extending support intermediate its ends arranged to engage the upper side of said diagonal shield, said check-pad holder also provided with a downwardly and backwardly extending portion adapted to engage the lower side of the upper edge of said diagonal shield. 10 15
